UNITED STATES PATENT OFFICE.

LOUIS STEINBERGER, OF BROOKLYN, NEW YORK.

SELF-COOLING STRAIN INSULATOR.

1,406,697.

Specification of Letters Patent. Patented Feb. 14, 1922.

Application filed December 10, 1918. Serial No. 266,050.

To all whom it may concern:

Be it known that I, LOUIS STEINBERGER, a citizen of the United States, and a resident of the borough of Brooklyn, city and

5 State of New York, have invented certain new and useful Improvements in Self-Cooling Strain Insulators, of which the following is a specification.

10 My invention relates to a strain insulator so constructed as to be self cooling when the interior of the same becomes heated electrically and which is at the same time provided with electrical conducting means to take care of any flash overs or leakage 15 currents which may occur.

One of the objects of my invention therefore is to provide a self cooling strain insulator provided with additional means for prolonging the life of the insulator.

20 Another object is to provide a strain insulator, the strain members of which are so arranged as to surround the ventilating conduit and also surround the electrical conducting means situated in the central portion 25 of the insulator body.

Another object is to provide a strain insulator provided with strain members embedded within the central portion thereof and arranged adjacent to a metal lined conduit passing through the central portion of 30 the insulator.

Other objects will appear from the subjoined specification and claims.

Referring to the drawings;

35 Fig. 1 is a vertical section through the central portion of my improved insulator, embodying my invention, portions of the insulator being shown in elevation.

40 Fig. 2 is a section on line 2—2 of Fig. 1. It is well known that in actual operation the insulating material, especially at the central portion of the insulator, becomes heated and thereby the insulator loses its efficiency. In other words, its efficiency is lowered, not only from an electrical standpoint but from a mechanical standpoint as well. If the heat is permitted to continue for a certain period of time the destruction of the insulator will follow.

45 The present invention is applicable to all insulators but especially to strain insulators and the insulator structure is so formed that the central portion thereof which heats rapidly, is provided with a metal lined venti- 55 lating means, permitting passage of the cool

air therethrough and the exit of the hot air, the metal lining forming a conducting path for flash over current between the strain members.

It is desirable to keep the central portion 60 of the insulator body which is adjacent the strain members as cool as possible, otherwise the insulating material when heated will so change in structure that the strain members will gradually move towards each 65 other, and it is obvious that as they so move the electrical value of the insulator is decreased.

Referring to the drawings, in which the same reference character indicates the same 70 part in the several views:

A is an insulator the body of which may be formed of any suitable insulating material, but I prefer to use the insulating material well known in the art as electrose. 75 B is the integral strain member made of metal and C is a two-part strain member also made of metal, which is provided with the well known means for connecting the two parts together, namely, one of the projecting ends 10 of the strain member is provided with screw threads which engage the screw threads in the socket 11 of the removable portion of the strain member. The sleeve 12 is screw threaded to the other projecting end 10' of the embedded portion of the strain member and to the abutting end 13 of the removable portion of the strain member. This means of connecting the two-part insulator so that said parts may 80 also be removed, is well known in the art and therefore only requires a general description. The body of insulating material is protected from being broken by the integral flanges 15 and 16 on the leg portions 17 and 18 of the embedded section of the two part strain member. 85

The strain members are also of the type invented by me and consist of ring shaped portions 20 and 30, said rings bridging the 100 upright portions respectively of the two strain members. The body portion of the insulator is molded about the strain members after they have been centered with respect to each other by bringing the ring 105 portions of each insulator opposite each other so that the rims of the ring portions will be in direct alignment, leaving a uniform space between the rings. The body of insulating material is molded about the as- 110

sembled interlocked strain members so as to form a shape as shown in the drawing, in which the insulating material is molded around the leg portions of each strain member to form projections 25, 26, 27 (the fourth not shown in the drawing) these projections abutting against the flanges 15 and 16 above referred to, and there is also a central, radially projecting flange 50 extending from 10 the insulator.

A central opening or conduit 60 is formed through the body of the insulator, said conduit continuing through the ring portions of the embedded strain members. In forming the conduit care has to be taken to provide a sufficient thickness of insulating material around the inner surfaces of the rings. To illustrate, if the diameter of the cross sections of the ring portions of the strain member are each one-half inch, and the inner diameters of the ring portions are each one and one quarter inch, the diameter of the central hole should be such that there will be left at least one-half inch thickness 25 of insulating material around the interior of the ring portions of the strain member. The thickness of insulating material at these points is preferably equal to the minimum thickness of insulating material around 30 the leg portion of the strain member, as at the parts α shown in the figure.

As will be seen, the centrally arranged hole passing through the body of the insulator and through the strain members permits of the ready ventilation of the insulator when it is in actual operation and connected to a line, thereby tending to cool the central portion of the insulator, thus preventing its destruction by the generated 40 heat.

The metallic tube 70, preferably of brass, is inserted in the conduit 60 and molded therein to form a metallic lining therefor.

As will be readily understood the metallic tube 70 does not normally carry any electric 45 current at all. Should, however, the voltage become sufficiently high, it will break down the air between the terminals or strain members, and the ends of the tube nearest there- 50 to. In other words, a path is provided for the current through the insulator rather than around the insulator, thereby affording protection to the insulator.

The flashover, above referred to between 55 the strain members and the ends of the metal tube, will occur when the insulator is in a perfect condition.

In practice, however, incipient flaws or imperfections may sometimes be present in 60 the central portion of the insulator body immediately surrounding the metal parts, and these imperfections may be magnified when the insulating body becomes heated while in use. Should such a condition exist and 65 the voltage become sufficiently high the body

of insulating material is in great danger of total destruction. My improved structure is therefore so designed and arranged that the puncture, if one takes place at all, will occur between the ring member and the 70 metal tube, thus causing a breakdown only at that point as the current will seek the tube and flow along the exposed surface of the same and arc to the exposed strain members. Before the insulator could be 75 totally destroyed it would have to puncture the insulating material at a different place from its first puncture and thereby go to ground and my invention is designed to prevent or minimize the danger of this occurrence. 80

The relation of the amount of insulation material between the two ring members 20 and 30 to the amounts of insulating material between either of the rings 20 or 30 and the 85 metal tube 70 is such that the current would seek the metal tube rather than to puncture the insulating material at any other point as the electric current always seeks the easiest path. 90

Owing to this construction in which the ventilating conduit is metal lined the life of the insulator is materially prolonged.

It is to be understood that the above description and drawings are merely illustrative and the invention is not to be limited in any respect, except as defined in the subjoined claims. 95

Having now described my invention what I claim as new and desire to secure by Letters Patent is:

1. A strain insulator including an insulating body provided with interlocking strain members partially embedded therein, said insulator having a metal lined ventilating conduit extending therethrough, said conduit passing through the oppositely disposed embedded portions of the strain members. 105

2. An insulator consisting of a body of insulating material, interlocking strain members embedded therein, said body of insulating material being provided with a ventilating conduit passing therethrough, said conduit also passing through the central 110 embedded portions of the strain members, and a metal lining for said conduit. 115

3. An insulator comprising a body of insulating material, strain members partially embedded therein, said body of insulating material being provided with an electrical tubular conducting member passing therethrough, said conducting member also passing through the central embedded portions 120 of the strain members. 125

4. An insulator, comprising a body of insulating material, strain members provided with centrally arranged bridge portions molded therein, said insulating body being provided with a ventilating metal lined con- 130

duit passing therethrough and also through the centrally arranged bridge portions of the strain members.

5. In an insulator, a body of insulating material, interlocking strain members molded therein, the central portions of the strain members situated opposite each other, the said central portions being ring shaped and a metal lined ventilating conduit passing through the body of the insulator and also through the ring portions of the strain members.

6. An insulator comprising a body of insulating material, interlocking strain members molded therein, the central portions of the strain members situated opposite each other, the said central portions being ring shaped and an electrical conductor passing through the body of the insulator and also 20 through the ring portions of the strain members.

7. An insulator comprising a body of insulating material, strain members provided with centrally disposed portions assembled

therein, said body of insulating material 25 being provided with an electrical conducting member passing therethrough, said conducting member passing through the embedded centrally disposed portions of the strain members.

8. An insulator comprising a body of insulating material, interlocking strain members provided with centrally disposed portions molded therein, the central portions of the strain members situated opposite to 35 each other, the said central portions being ring shaped and an electrical conductor passing through the body of the insulator and also through the ring portions of the strain member.

In witness whereof, I have hereunto set my hand at the borough of Manhattan, city and State of New York, this 27th day of November, 1918.

LOUIS STEINBERGER.

In presence of—
ZITA M. GRAHAM.
